United States Patent Office.

DANIEL C. RIPLEY, OF BIRMINGHAM, PENNSYLVANIA.

Design No. 3,842, dated February 8, 1870.

DESIGN FOR BAPTISMAL FONT.

The Schedule referred to in these Letters Patent and making part of the same.

To all whom it may concern:

Be it known that I, DANIEL C. RIPLEY, of Birmingham borough, in the county of Allegheny, and State of Pennsylvania, have invented a new and useful Design; and I do hereby declare the following to be a full, clear, and exact description thereof, reference being had to the accompanying drawing, forming a part of my specification, which represents a front elevation of my improved design, which design consists in a font, bowl, or basin, mounted on a foot or stem between arms extending out radially, such arms being intended for use as candlesticks or lamp-stands.

To enable others skilled in the art to make and use my invention, I will proceed to describe the same.

In connection with the religious exercises of some churches, a font or bowl is desired for baptismal or other sacred uses, and in the same connection, sometimes the burning of candles or tapers is obligatory.

For these uses I make a support of any suitable character, terminating at its upper end in a stem, *b*, and cause such stem to branch from at or near its upper end, into arms *a a* of any desired length, their outer ends being fitted with sockets *e e* for candles or

tapers, or otherwise adapted for use with suitable means of illumination.

Between these arms, and on or directly over the stem *b*, I mount a bowl, *d*, of any desired form, which is designed for use as a baptismal font, or for other like uses. On this a cover, *d'*, may be used, if so desired.

The parts named are pressed from glass, or blown and pressed in any of the ways known to the art.

Any suitable style of ornamentation may be pressed, cut, or engraved on the bowl.

What I claim as my invention, and desire to secure by Letters Patent, is—

The improved design, consisting of a bowl, font, or basin, arranged on a stem or base, and between radially diverging arms, substantially as described and shown.

In testimony whereof, I, the said DANIEL C. RIPLEY, have hereunto set my hand.

DANIEL C. RIPLEY.
